UNITED STATES PATENT OFFICE.

GEORGE H. COLE, OF WENONA, ILLINOIS.

PERFORATING AND SCORING ATTACHMENT FOR PRINTING-PRESSES.

1,270,788.

Specification of Letters Patent.

Patented July 2, 1918.

Application filed August 28, 1917. Serial No. 188,567.

To all whom it may concern:

Be it known that I, GEORGE H. COLE, a citizen of the United States, residing at Wenona, in the county of Marshall, State of Illinois, have invented certain new and useful Improvements in Perforating and Scoring Attachments for Printing-Presses, of which the following is a description, reference being had to the accompanying drawings, forming a part hereof.

The object of the invention is to provide an alternative perforating, scoring and cutting attachment for printing presses which may be used in connection with or in substitution for a gripper, for actuation by the platen or equivalent element of a printing press, such device being adapted for a ready interchange of blades to suit the operation to be performed, to be readily attachable to the press, and being of simple construction and capable of economical manufacture.

With these and similar objects in view, as will appear in the course of the following description, the device embodies a construction, combination and relation of parts hereinafter fully set forth, it being understood that changes in form, proportion and minor details may be resorted to, within the scope of the appended claim, without departing from the spirit of the invention.

In the drawing:

Figure 1 is a reverse or bottom plan view of the attachment.

Fig. 2 is a longitudinal, sectional view of the same.

Fig. 3 is a top plan view.

Figs. 4, 5 and 6 are side views of interchangeable blades for use in connection with the attachment.

Fig. 7 is a detail, transverse section on the plane indicated by the line 7—7 of Fig. 2.

Fig. 8 is a detail, transverse section on the plane indicated by the line 8—8 of Fig. 2.

Fig. 9 is a plan view in detail of one end of the device, showing the same partly in section on the line 9—9 of Fig. 2.

The device embodying the invention consists essentially of a main element 10 which may be used upon or in substitution for the ordinary gripper bar of a printing press and therefore, for convenience, may be termed a gripper bar, being provided at one end with an enlargement 11 having an opening 12; a blade 13 disappearingly mounted in a slot 14 in the main element, and a carrier 15 sup-

porting such blade and in which the latter is removably seated so as to provide for an interchange of blades having operating edges adapted to perform work of different kinds as for example, perforating, scoring, cutting and the like.

The seat 16 in the carrier is of a length less than the carrier to sufficiently accommodate a blade of the maximum required length for any kind of work which may be contemplated with reference to the press, and the blade is held in the seat by a removable means for example as transverse pins or keys 17, and the operating edge whether of the perforating type shown in Figs. 4 and 5, or of the scoring or cutting type indicated in Fig. 6, may extend either throughout the full length of the blade, or only a portion thereof as shown in Fig. 4 and also in Fig. 2, the total length of the blade, however, being the same in all cases, so that the same securing means arranged in the same way may be employed for all blades.

The guiding means for the carrier, to direct its movement to and from the main element or gripper bar, preferably consists of guide pins 18 in the form for example of screws terminally threaded as at 19 in the main element or gripper bar and operating in an opening in the carrier, said screws being headed as at 20 to form stops to limit the outward or upward movement of the carrier, or the movement from the main element or gripper bar, and in terminal arrangement with the ends of the carrier are leaf springs 21 constituting means for yieldingly holding the carrier and therefore the operating blade in retracted or inoperative position, said springs being suitably attached as at 22 to the main element or gripper bar.

It will be understood that in the operation of the press to which the device of the invention has been applied, the successive actions of the platen serve to depress the carrier and force the operating edge of the blade supported thereby into or through the paper or cardboard which is being manipulated; and also that an interchange of blades, to suit the prospective work may be made merely by withdrawing the locking pins or keys and after displacing one blade substituting another through the slot in the main element or gripper bar, followed of course by the replacing of the keys.

A single guide-pin is preferably used at each end of the carrier in alinement with

the slot in the gripper bar and the springs engage the carrier at their over hanging extremities, beyond the guide-pins, as by this arrangement the construction is simplified, 5 the possibility of binding of the parts in operation is eliminated or reduced to the minimum, and the gripper bar and carrier may be made of the minimum width commensurate with the required strength. The 10 guiding and retracting means are arranged so as to offer no obstruction at either side of the plane of the slot in the gripper bar.

Having described the invention, what I claim is—

15 A perforating or scoring attachment for printing presses, having a gripper bar provided with a longitudinal slot, a blade dis-
appearingly mounted in the slot of the gripper bar, a carrier of a length exceeding that

of said slot and provided with a blade receiving seat registering and coextensive with the slot of the gripper bar, means for detachably securing the blade in said seat, a guide pin connecting the carrier with the gripper bar beyond each extremity of the seat in the former and on the line thereof and having stops for limiting the separation of the carrier and gripper bar, and springs engaging the extremities of the carrier beyond the guide pins for yieldingly main- 20 25 30 taining the separation of said parts.

This specification signed and witnessed this 24 day of August A. D. 1917.

GEO. H. COLE.
